UNITED STATES PATENT OFFICE.

GEORGE MACHLET, ELIZABETH, ASSIGNOR TO EDWARD P. REICHELM, OF JERSEY CITY, NEW JERSEY.

HYDROCARBON-BURNER.

SPECIFICATION forming part of Letters Patent No. 325,617, dated September 1, 1885.

Application filed July 15, 1885. (No model.)

To all whom it may concern:

Be it known that I, GEORGE MACHLET, of Elizabeth, in the county of Union and State of New Jersey, have invented certain new and 5 useful Improvements in Hydrocarbon-Burners, of which the following is a specification.

This invention has reference to an improved hydrocarbon-burner for metallurgical and other furnaces by which a perfect combustion 10 and a high degree of heat are produced, so that it works in a quicker and more economical manner than the gas-burners heretofore employed for jewelers' and other furnaces.

The invention consists of a hydrocarbon- 15 burner for furnaces, which is provided with a steam-superheating coil located in the nozzle of the burner, a vapor-conducting tube leading to said nozzle, an injector connected to the superheater, a supply-pipe for the volatile 20 hydrocarbon oil, a mixing-chamber, an evaporating steam-coil in said mixing-chamber, and a trough below said evaporating-coil.

The invention consists, further, of certain 25 details of construction and combination of parts, which will be described more fully hereinafter, and finally pointed out in the claims.

In the accompanying drawings, Figure 1 represents a vertical longitudinal section of my improved hydrocarbon-burner, shown as 30 applied to a metallurgical furnace. Fig. 2 is an end elevation of the mixing-chamber, showing the evaporating-coil and its trough.

Similar letters of reference indicate corresponding parts.

A in the drawings represents a metallurgical or other furnace, and B a metallic nozzle or throat, that communicates with the interior of the furnace. In the nozzle or throat B is located a steam superheating coil, C, to which 40 the steam is supplied at the upper end by a steam-pipe, C'. The superheater C is connected at the lower end by a pipe, C², to an injector, D, that is located axially in line with a mixing-chamber, E. The mixing-chamber 45 E is contracted in front of the injector D, and connected by a bent tube, E', with the nozzle B. The eduction-pipe C² of the superheater C is also connected with a steam-coil, F, that is located in the mixing-chamber E, back of the injector D, said coil serving to evaporate

the hydrocarbon oil that is supplied by a pipe, f. The diameter of the pipe forming the evaporation-coil F is made smaller than the diameter of the pipe leading to the injector D, so that the steam passes with greater force 55 through the injector than through the coil F. The opposite end of the evaporating-coil F is open and discharges the steam and water of condensation formed in the coil into the atmosphere. A trough or drip-pan, f', is arranged below the coil F at the lower part of the mixing-chamber E, said drip-pan collecting the oil not vaporized by contact with the coil, so as to evaporate by the radiant heat of the coil. .

The injector draws atmospheric air into the mixing-chamber E, and forces the same, together with the hydrocarbon vapors and the superheated steam emitted by the injector through the tube E' and nozzle B, into the 70 furnace, where the combustion of the gas, air, and steam mixture takes place. The heat produced by the combustion causes the dissociation of the superheated steam into its component elements, so that a perfect and 75 rapid combustion of the fuel and a high temperature are produced in the furnace.

The bent connecting-tube E' is provided, at its bottom portion, with an opening, g, closed by a thin plate, g', of brass or other suitable 80 metal, which is retained by a collar, g'', attached to the tube E'. The plate g serves for the purpose of furnishing an outlet for the molten metal in the furnace in case the crucible containing the same should break. The 85 mixing-chamber, injector, and evaporating-coil are thereby protected against destruction by the molten metal in case of accident.

Having thus described my invention, I claim as new and desire to secure by Letters Patent— 90

1. A hydrocarbon-burner for metallurgical and other furnaces, consisting of an eduction nozzle or throat, a steam-superheating coil located in said nozzle, a mixing-chamber, a tube connecting said mixing-chamber and nozzle, an injector connected to the superheater, an evaporating-coil also connected to the superheating-coil, and a tube for supplying hydrocarbon oil to the evaporating-coil, substantially as set forth.

2. The combination of an eduction throat or nozzle, a steam-superheating coil located in said nozzle, an injector connected to said superheater, a mixing-chamber surrounding the injector, a tube connecting the contracted end of the mixing-chamber with the nozzle, an evaporating-coil located in the mixing-chamber and connected to the superheater, a hydrocarbon-supply pipe, and a trough or drip-pan below said evaporating-coil and supply-tube, substantially as set forth.

3. The combination of an eduction-nozzle, a steam-superheater within said nozzle, an injector connected with said superheater, an evaporating-coil also connected to the super-

heater, a mixing-chamber surrounding the injector and evaporator, a bent tube connecting the mixing-chamber and nozzle, said tube having a bottom opening closed by a sheet-metal plate, a hydrocarbon supply-pipe terminating in the evaporating-coil, and a trough or drip-pan below the same, substantially as set forth. 20

In testimony that I claim the foregoing as my invention I have signed my name in presence of two subscribing witnesses. 25

GEORGE MACHLET.
